UNITED STATES PATENT OFFICE

J. DUDLEY WAITE, OF HAMDEN, ASSIGNOR TO HIMSELF AND JAMES L. ROOT, OF NEW HAVEN, CONNECTICUT.

IMPROVEMENT IN HOLLOW AUGERS.

Specification forming part of Letters Patent No. 151,178, dated May 19, 1874; application filed February 11, 1874.

To all whom it may concern:

Be it known that I, J. DUDLEY WAITE, of Hamden, in the county of New Haven and State of Connecticut, have invented a new Improvement in Hollow Augers; and I do hereby declare the following, when taken in connection with the accompanying drawings and the letters of reference marked thereon, to be a full, clear, and exact description of the same, and which said drawings constitute part of this specification, and represent, in—

Figure 1, a side view; and in Fig. 2, a cutting-end view.

This invention relates to an improvement in what are known as "hollow augers"—that is, the tool which is used for forming the tenon on the outer end of carriage-wheel spokes and for like purposes.

One great difficulty in the use of this class of tools is to prevent the accidental displacement of the cutter, in consequence of which the diameter of the tenon is varied.

The object of this invention is to so seat the cutter that it cannot be accidentally displaced, and also to prevent the splitting or forming of a burr at the edge of the cut; and the invention consists in making the seat transversely concave and the cutter correspondingly con-

cavo-convex, or gouge shape, as more fully hereinafter described.

A is the barrel or body; B, the tang; C, the flange of the head, through an opening, D, in which the cutter E is set, the said opening D forming the throat. The seat for the cutter is made transversely concave, as seen in Fig. 2, and the cutter E correspondingly convex upon its under surface, so as to fit closely in the seat, as seen in Fig. 2. The cutter is made correspondingly concave upon its face, which gives to the cutting-edge a gouge shape, and causes the extreme cut to be inward, which prevents splitting or forming a burr at the edge.

I do not broadly claim a gouge-shaped cutter set in a concave seat.

I claim as my invention—

As an article of manufacture, the herein-described hollow auger, consisting of the body A, tang B, flange C, throat D, and cutter E, when the seat for the said cutter is made transversely concave and the cutter correspondingly concavo-convex, substantially as specified.

J. DUDLEY WAITE.
